TICKET PUNCH

Clarence S. Davis, South Braintree, Mass.

Application July 21, 1931. Serial No. 552,109

10 Claims. (Cl. 164—120)

This invention relates to ticket punches and particularly to that class of punches which are adapted to punch a round hole in a card, the object of the invention being the production of a

5 compact easily-operated punch provided with a compartment to receive all the disks punched from the ticket or card.

This object is attained by the device illustrated in the accompanying drawing.

10 For the purpose of illustrating the invention, one preferred form thereof is illustrated in the drawing, this form having been found to give satisfactory and reliable results, although it is to be understood that the various instrumentalities 15 of which the invention consists can be variously arranged and organized, and the invention is not limited to the precise arrangement and organization of these instrumentalities as herein shown and described except as required by the scope of 20 the appended claims.

Of the drawing:

Figure 1 represents a side elevation of a ticket punch embodying the principles of the present invention.

25 Figure 2 represents a front elevation of same. Figure 3 represents a vertical longitudinal section of same on line 3, 3, on Fig. 2.

Figure 4 represents a transverse vertical section on line 4, 4, on Fig. 3.

30 Figure 5 represents a transverse vertical section on line 5, 5, on Fig. 3.

Figure 6 represents a longitudinal section on line 6, 6, on Fig. 3, and

35 Figure 7 represents a horizontal section on line 7, 7, on Fig. 3.

Similar characters indicate like parts throughout the several figures of the drawing.

In the drawing, 10 and 11 are two halves of the casing of a ticket punch, the part 11 having 40 formed on its inner face two cylindrical projections 12 and 13.

On the projection 13 is mounted an actuating lever 14 having a gear segment 15 on its inner end within said casing.

45 The outer end of the lever 14 has a downwardly projecting lug 16 formed thereon which is surrounded by the upper end of a spring 17, the lower end of which surrounds the upwardly projecting lugs 18 and 19 formed respectively on the

50 two halves 10 and 11 of the casing.

The lugs 12 and 13 are formed on an upward extension 21 of the part 11 of the casing, the part 10 having a similar upward extension 20.

55 These two upward extensions are preferably spot-welded face to face and the adjacent faces

have oppositely disposed semi-cylindrical depression 22 forming a bearing in which is disposed a punching member 23 adapted to reciprocate vertically.

This punching member 23 has rack teeth 24 formed on one side thereof meshing with the teeth of a pinion 25 mounted on the lug 12, the teeth of this pinion 25 also meshing with the teeth of the gear segment 15.

The lower part 26 of the casing is in the form 65 of an elongated cylinder, as shown in the drawing, the inner end of which is permanently closed while the outer end thereof is normally closed by a cap 27.

This cap has secured thereto one end of a rod 70 28 having an eye 29 therein, the inner end of the rod extending through a lug 30 formed on the part 11 and said inner end of rod 28 has a lateral bend 31 therein, as shown in Fig. 3.

Between the eye 29 and the lug 30 and secured 75 thereto is a helical spring 32 which normally retains the cap 27 in closed position, as shown in Fig. 6.

Between the cylindrical portion 26 and the forwardly projecting portions of the extensions 80 20, 21 is a space or slit 33 which permits a ticket to be inserted beneath the punching member 23.

Immediately beneath and coinciding with the bearing 22, 22 is a cone-shaped opening 34 communicating with the interior receptacle 28 of 85 the cylindrical portion 26 of the ticket punch.

The opening 34 has a greater diameter at the bottom than at the top, thus forming at the top a shearing edge of the same diameter as the diameter of the punching member 23.

The upper portion of the forward end of the cylindrical part 26 beneath the slit 33 is built up 90 to form a flat face 33x as shown in Fig. 4.

The spring 17 normally retains the lever 14 in the position indicated in Figs. 1 and 3 of the drawing with the punching member 23 in raised position, as shown in Fig. 3.

When hand pressure is applied to the lever 14 to move it in the direction of the arrow a, (see 100 Fig. 1) against the tension of the spring 17, the gear segment 15 will rotate the pinion 25 and cause a downward movement of the punching member 23.

During this downward movement of the punch 105 member 23 it will pass through any ticket or other cardboard inserted in the slot or space 33 and resting on the flat face 33x.

As the punching member 23 enters the opening 34 and coacts with the shearing edge thereof, it 110

will cut from said ticket a disk which will drop into the receptacle 28.

As soon as pressure is removed from the lever 14 the spring 17 will return the various elements 5 to their normal position ready for another operation.

The forward end of the upward extensions 20, 21 have oppositely disposed passages 35 which form a sight opening and permits the operator 10 to see the upper part of the printed ticket and thereby more accurately position the punching member relatively thereto during the punching operation.

The elongated cylindrical portion 26 of the 15 casing makes a smooth surface for the hand to grip when operating the punch and at the same time provides an inner receptacle 28 which will receive innumerable punches before it is necessary to empty the receptacle.

20 When it is desired to remove the punched disks from the receptacle 28, the operator seizes the closing cap 27 and moves it outwardly until the lateral bend 31 in the rod 28 comes into contact with the lug 30, and the cap 27 is in the position 25 indicated by dotted lines at 36 on Fig. 3.

The disks punched from the ticket may then be readily removed from the open end of the receptacle 28 by shaking the casing while held with the open end of cylinder 26 extending downwardly.

When the various parts of the ticket punch are assembled as shown in the drawing, the two halves of the casing are spot-welded together at various points, as indicated by dotted lines 37, 35 on Fig. 1 of the drawing.

If desired, the two parts 10, 11 of the casing may be secured together by other means without departing from the invention.

This makes a very compact ticket punch which 40 may be manufactured at slight cost and will be very effective in use.

It is believed that the operation and many advantages of the invention will be understood without further description.

45 Having thus described my invention, I claim:

1. A ticket punch comprising an elongated hollow cylindrical hand-gripping portion having an upward and forward chambered extension separated at its forward end from said cylindrical portion by a narrow ticket-receiving slit, said cylindrical portion having near its rear end an upward projection; a vertical punching member adapted to reciprocate in a cylindrical bearing in the forward end of said extension the 55 lower end of which is adapted to coact with an opening in the upper wall of said hollow cylindrical portion, said punching member having rack teeth; a freely rotatable gear within said extension and meshing with said rack teeth; a lever pivoted to said extension having at the 60 forward end thereof within said extension a gear segment meshing with said gear and provided near its outer end with a downward projection; and a spring between said lever and receptacle 65 with its opposite ends surrounding said projections.

2. A ticket punch comprising a casing the lower portion of which consists of a hollow cylindrical hand grip; a vertically reciprocating cylindrical punching member of the same diameter throughout and having rack teeth enclosed within the upper part of said casing; a gear enclosed within said upper part meshing with said rack teeth; and a spring-pressed lever pivoted to 70 said upper part and having one end thereof

within said casing provided with a gear segment meshing with the teeth of said gear.

3. A ticket punch comprising a casing having at its lower end a hollow cylindrical hand grip; a vertically reciprocating cylindrical punching member having rack teeth enclosed within an upwardly extending branch of said casing and having an inclined face at its lower end; a gear enclosed within said branch meshing with said rack teeth; and a spring-pressed lever pivoted to said branch and having at one end thereof within said branch a gear segment meshing with the teeth of said gear, said hollow hand grip extending beneath said punching member and adapted to receive the disks punched from a card.

4. A ticket punch comprising a hollow cylindrical hand grip having at one end an upwardly and forwardly extending branch separated therefrom by a narrow slit; a vertically reciprocating cylindrical punching member having rack teeth enclosed within said branch, said member being of the same diameter throughout its length; a gear enclosed within said branch meshing with said rack teeth; a spring-pressed lever pivoted to said branch and having at one end thereof within said branch a gear segment meshing with the teeth of said gear, said hollow hand grip extending beneath said punching member and adapted to receive the disks punched from a card; and a movable closure for the outer end 100 of said hollow hand grip.

5. A ticket punch comprising a casing in two vertical parts secured together and having cylindrical lugs formed integral with one part and forming pivot members, the lower portion of said 110 two-part casing consisting of a hollow cylindrical hand grip; a gear loosely mounted on one of said lugs; a lever pivotally mounted on another lug and having at its inner end a gear segment within said casing meshing with said gear; a vertical cylindrical punching member of equal 115 diameter throughout its length disposed within an upper branch of said casing and having rack teeth meshing with said gear; and a spring extending from the top of said cylindrical hand grip for retaining said lever in normal position.

6. A ticket punch comprising a casing in two vertical parts secured together and having cylindrical lugs formed integral with one part and forming pivot members, the lower portion of said 120 two-part casing consisting of a hollow cylindrical hand grip; a gear loosely mounted on one of said lugs; a lever pivotally mounted on another lug and having at its inner end a gear segment within an upward branch of said casing 125 meshing with said gear; a vertical punching member of equal diameter throughout its length disposed in grooves in the two parts of said branch and having rack teeth meshing with said gear; and a spring for retaining said lever in 130 normal position; said hollow hand grip extending beneath said punching member and being provided with an opening to receive the punchings.

7. A ticket punch consisting of a casing having at one end a ticket-receiving slit; a vertical cylindrical punch of equal diameter throughout its length disposed above said slit and reciprocable in a bearing formed in said casing, said punch having rack teeth and a bevelled face at its lower end; a gear within said casing meshing with said rack teeth; a pivoted spring-pressed lever provided with a gear segment within said casing meshing with said gear; and means beneath said slit coacting with the bevelled lower face of said 135 140 145 150

plunger to effect a punching operation and receive the punchings.

8. A ticket punch consisting of a casing having at one end a ticket-receiving slit and a cylindrical bearing above and perpendicular to said slit; a cylindrical punch in said bearing having enclosed rack teeth; an enclosed gear in said casing freely rotatable and meshing with said rack teeth; and a pivoted spring-pressed lever 10 extending into said casing and provided on its inner end with a gear segment meshing with said gear.

9. A ticket punch consisting of a casing having at one end a ticket-receiving slit and a cylindrical bearing above and perpendicular to said slit; a cylindrical punch in said bearing having enclosed rack teeth, said punch having the same diameter throughout its length; an enclosed gear 15 in said casing freely rotatable and meshing with said rack teeth; a pivoted spring-pressed lever 20

extending into said casing and provided on its inner end with a gear segment meshing with said gear; and a plate on said casing beneath said slit provided with a cone-shaped opening to receive the lower end of said punch during the punching operation.

10. A ticket punch consisting of a casing having at one end a ticket-receiving slit and a cylindrical bearing above and perpendicular to said slit; a cylindrical punch in said bearing having enclosed rack teeth, said punch having the same diameter throughout its length; an enclosed gear in said casing freely rotatable and meshing with said rack teeth; a pivoted spring-pressed lever extending into said casing and provided on its inner end with a gear segment meshing with said gear; and means within said casing and beneath said slit adapted to receive the punchings.
